UNITED STATES PATENT OFFICE.

PIERRE DE CHAIGNON LA ROSE, OF CAMBRIDGE, MASSACHUSETTS, ASSIGNOR TO THE CATHOLIC STUDENTS' MISSION CRUSADE, OF CINCINNATI, OHIO, A FIRM COMPOSED OF HENRY MOELLER, FRANK J. BECKMANN, FRANK A. THILL, ROBERT B. RIORDAN, WILLIAM B. FOLEY, AND F. J. HELM.

DESIGN FOR A FLAG.

Application filed December 31, 1923. Serial No. 8,204. Term of patent 14 years.

To all whom it may concern:

Be it known that I, PIERRE DE CHAIGNON LA ROSE, a citizen of the United States of America, and a resident of Cambridge, in the county of Middlesex, State of Massachusetts, have invented a new, original, and ornamental Design for a Flag, of which the following is a specification, reference being made to the accompanying drawing, forming a part thereof.

The figure is a view of a flag, showing my new design.

I claim:

The ornamental design for a flag, as shown.

PIERRE DE CHAIGNON LA ROSE.
